UNITED STATES PATENT OFFICE.

CLAUDE HAMERTON ROWE, OF HUSTHWAITE, EASINGWOLD, ENGLAND.

DEVICE FOR PREVENTING LEAKAGE OF AIR AROUND THE STEMS OF VALVES OF INTERNAL-COMBUSTION ENGINES.

Application filed April 13, 1920. Serial No. 373,476.

To all whom it may concern:

Be it known that I, CLAUDE HAMERTON ROWE, a subject of the King of Great Britain, residing at Husthwaite, Easingwold, in 5 the county of York, England, have invented certain new and useful Improvements in a Device for Preventing Leakage of Air Around the Stems of Valves of Internal-Combustion Engines, of which the following 10 is a specification.

The present invention refers to a device for internal combustion engines designed to prevent leakage of air between the stem of a valve and the valve guide through which 15 it passes; the invention refers to that kind or type of such device which comprises a tubular sleeve open at one end, having a through aperture at the opposite otherwise closed end, and an annular washer of felt 20 or the like located within said sleeve and bearing on said closed end. Such a sleeve is utilized by being passed over the valve stem around which the felt washer closely fits, the upper end of the sleeve being passed 25 over the valve guide, and the sleeve is formed with an external flange against which the ordinary valve spring acts to retain the sleeve in position and to press said washer between the said valve guide and the 30 base of the sleeve.

The valve guides however to which such sleeves are to be fitted, that is over which they are to be passed, frequently vary in diameter, and even sometimes in formation, 35 some such valve guides being conical, and consequently it is requisite that in the manufacture such sleeves must be made in varied sizes and in shapes also, and since the tools required for the manufacture of the sleeves 40 are costly, these considerations are detrimental to their general employment.

Now the object of the present invention is to so construct such a sleeve that it will be universally applicable to differing sizes and 45 shapes of valve guides, all as hereafter described and claimed.

The invention will be described with reference to the accompanying drawings, wherein in Fig. 1 shows the improved device fitted 50 to a valve guide with vertical sides, and Fig. 2 shows a modified construction of the device fitted to a valve guide which is conical in shape.

Fig. 3 shows in vertical section and plan 55 view one construction of the sleeve as fitted

to Fig. 1, Fig. 4 show another construction as fitted to Fig. 2, and Fig. 5 is a front elevation of a modified construction of the sleeve shown in Fig. 3.

Referring to Figs. 1 and 3, the sleeve is 60 formed with a base part 1 having a central aperture 2 through which the valve stem 3 passes, and within the sleeve on the base part 1 is located a washer 4 of soft material, such as felt, having a central aperture coinciding 65 with the aperture in the base part 1.

Proceeding from the base part 1 and bent in an upward direction are a plurality of separate arms 5 adapted to pass over and embrace the usual valve guide 6. The upper 70 ends of the arms 5 of the sleeve are bent outwardly to form outwardly extending flanges 7, which must abut against the special seat of the valve spring 9 to which reference is hereinafter made.

It will be readily understood that such a sleeve can be employed for a valve guide such as 6, or it could be applied even if the valve guide was of larger diameter than the normal internal diameter of the sleeve, by 80 the arms 5 being distanced from one another sufficiently to pass over the valve guide. Similarly such a sleeve is applicable even where the valve guide 6 is conical as at Fig. 2.

The stem of the valve passes as aforesaid through the soft washer 4 which fits the stem and through the aperture of the base part 1, and the valve guide is fitted with the usual abutment washer 8 which supports the lower end of the usual valve spring 9, and the upper end of the valve spring 9 bears beneath the flanged ends 7 of the arms 5 of the sleeve.

In the construction of sleeve just described the manufacture can be conveniently carried out by stamping a blank out of sheet metal and bending up the arms 5 into the position shown at Figs. 3 and bending over the flanges 7.

Obviously, as shown in Fig. 5, some of the arms 5 may be shorter than the others, merely serving the office of retaining the felt washer 4 in position and form.

In the modified construction of the sleeve 105 at Figs. 4, the base part 1 is formed cup-shaped, the separate arms 5 proceeding upwards from the edge of the cup, and such a construction is shown as applied at Fig. 2.

As shown at Figs. 1 and 2 of the draw- 110

ings, the length of the upstanding arms is such that their upper flanged ends will have a bearing upon the collar 10 of the valve guide 6, or equivalent abutment, so that the upper ends of the arms 5 are held against the collar 10 and the washer 4 is thus maintained under constant and substantially unvarying pressure.

What I claim as my invention and desire to secure by Letters Patent is:—

1. A washer supporting device for valves comprising an annular washer supporting body having radially disposed flexible arms, said arms adapted to be bent substantially perpendicular to the plane of said annular body and said arms being provided with out-turned flanges adjacent their free ends,

said flanges constituting abutment members.

2. A washer supporting device for valves comprising a cup shaped part adapted to 20 seat a washer the bottom of said cup having an orifice for the passage of a valve stem, and a plurality of flexible arms extending in spaced relation from the marginal edge of said cup part, said arms having their 25 ends out-turned to constitute abutment members.

In witness whereof I have hereunto set my hand in the presence of two witnesses:

CLAUDE HAMERTON ROWE.

Witnesses:

THOMAS WILLIAM ROGERS,
CYRIL GRIFFITH BREWER.
